UNITED STATES PATENT OFFICE

156,880

WASHING MACHINE

Robert C. Gwin, Jr., Barrington, R. I.

Application June 18, 1949, Serial No. 3,383

Term of patent 14 years

(Cl. D49—1)

To all whom it may concern:

Be it known that I, Robert C. Gwin, Jr., a citizen of the United States, residing at Barrington, State of Rhode Island, have invented a new, original, and ornamental Design for a Washing Machine, of which the following is a specification, reference being had to the accompanying drawing, forming a part thereof.

Fig. 1 is a perspective view of a washing machine embodying my new design; and

Fig. 2 is a perspective view thereof showing the washing machine with the cover removed.

I claim:

The ornamental design for a washing machine, substantially as shown.

ROBERT C. GWIN, JR.
